UNITED STATES PATENT OFFICE.

JOHN LEMMAN, OF WAKEFIELD, MASSACHUSETTS.

CAR-SEAT.

SPECIFICATION forming part of Letters Patent No. 487,034, dated November 29, 1892.

Application filed February 10, 1892. Serial No. 420,991. (No model.)

To all whom it may concern:

Be it known that I, JOHN LEMMAN, a citizen of the United States, residing at Wakefield, in the county of Middlesex and State of Massachusetts, have invented certain new and useful Improvements in Car-Seats; and I do hereby declare the following to be a full, clear, and exact description of the invention, such as will enable others skilled in the art to which it appertains to make and use the same.

My invention is an improvement in car-seats; and it consists in the novel features of construction and combination of parts hereinafter fully described.

15 In the accompanying drawings I have shown several forms in which I have contemplated embodying my invention, and said invention is fully disclosed in the following description and claims:

20 Referring to the said drawings, Figure 1 is a view of one of the sides of a car-seat embodying my invention from the inner side, showing the position of the seat and back cushions in dotted lines. Fig. 2 is a longitudinal sectional view of the seat portion.

25 Fig. 3 is a detail view of the rocker of the seat, with its operating-arm connected thereto. Fig. 4 is a similar view of a slightly-modified arrangement of parts. Fig. 5 is a similar view showing still another slight modification of the arrangement of said parts.

In the drawings, A represents the side frame of a car-seat constructed in the usual or ordinary manner, having the supporting or 35 foot portion *a* and the seat-arm *a'*, provided with brackets *a²* to receive the pivoted striker-arm, and said brackets may be provided with the usual latch, if desired. The side frame A is also provided with a support for the seat portion, which consists of a track or way A', having its ends curved or bent upwardly, as at *a³*.

B is the seat proper, which consists of the end pieces or rockers *b* and suitable connecting-framework, the said rockers having their ends curved or beveled. The rockers *b* are adapted to engage the ways or supports A' of the side frames of the car-seat, and when the forward or rear ends of the rockers are made 45 to engage the upwardly curved or bent portions of the ways or tracks of the sides the

seat is held in an inclined position, as will be seen in Fig. 1.

The back C is formed in the usual manner and provided with the end irons *c*, which are 55 connected to the side frames by the striker-arms D, pivotally attached to the side frames at *d* and pivoted to the end irons *c* at *d'*, and by the seat-operating arms E, which are pivoted to the side frames at *e* and to the end irons 60 at *e'*. I prefer that the striker-arms should be pivoted to the end irons *c* at points slightly above the center of the back and that the seat-operating arms should engage the back adjacent to the lower edge of the *same*, as 65 this forms the most graceful and convenient arrangement of parts. The seat-operating arm or lever E is nearly parallel to the striker-arm D when the latter is in engagement with one of the brackets *a²* and is of such length 70 that when the seat is shifted it will pass beneath the point *d*, where the striker-arm is pivoted to the side frame, as clearly shown in Fig. 1 in dotted lines.

The seat-operating arm is connected with 75 the seat in such a manner that when the back is raised and swung over to the other side of the side frames the said arm E will thrust the seat in the opposite direction, causing the rockers *b* to slide along the supports or guide-ways A' and engage the upwardly-extending portions of the same, thereby elevating the edge of the seat which is opposite the back, as will be readily understood. I may effect 80 the connection between the arm E and the seat in various ways. In Figs. 1 and 3 I have shown the arm E provided with an extension *e²*, which is provided with a lug or pin *e³*, engaging an elongated slot or recess *b³* in the rocker *b*, thus, causing the seat to move in 85 the required manner when the back is moved from one side to the other. In Fig. 5 I have shown this arrangement reversed and the rocker *b* provided with a pin or lug *b⁴* to engage an elongated slot or recess *e⁴* in the arm 90 E. In Fig. 4 I have shown a link F connecting the extension *e²* of the arm E with the rocker *b*, which will effect the same results in imparting the desired movements to the seat, the said link being pivoted to the rocker 95 at *e⁵*, as shown. In this form the arm E will be pivoted to the seat-frame by the pin *e*.

The operation of my improved car-seat will be apparent from the drawings. When it is desired to reverse the seat, the back is raised and moved to the other side of the side frames, the striker-arms and seat-operating arms moving in the arcs indicated by dotted lines in Fig. 1. The seat will be moved by the arms E and caused to travel along the guideways A' until the rockers b engage upwardly-extending portions of the said guideways, when the seat will be raised on the edge opposite the back and given the desired inclination.

It will be noticed that in the constructions herein shown and described the seat-operating parts are so formed that when the seat is in normal condition with the back in either position the seat will be locked, so that pressure exerted upon it in a horizontal direction will have no tendency to change the positions of the said operating parts, the seat-operating arms E and the part or parts connecting them with the seat proper being at such times in almost a horizontal line.

25 I do not desire to be limited to the exact details of construction herein shown and described, as variations may be made in the same without departing from the spirit of my invention.

30 What I claim, and desire to secure by Letters Patent, is—

1. In a reversible car-seat, the combination, with the main frame, back, and seat, of a link at each end of the car-seat, pivotally connected with the upper part of the back and the main frame, forming the striker-arms, and a seat-operating link at each end of the car-seat, disposed in an approximately horizontal position when the back and seat are in position for use, pivotally connected with the lower part of the back and with the main frame, and having, also, a connection with the seat, the connections of each of said seat-operating links with the seat, back, and main

frame being approximately in a straight line 45 and the connections of the said seat-operating links with the seat and main frame including a compensating connection with one of said parts, substantially as described.

2. In a reversible car-seat, the combination, 50 with the main frame, seat, and back, of a link at each end of the car-seat, pivotally connected with the upper part of the back and the main frame, forming the striker-arms, and a seat-operating link at each end of the car-seat, pivotally connected at one end with the back and having a pivotal connection with the main frame and a connection with the seat, the connection of each of the said seat-operating links with the seat and main frame 55 including a slotted construction, the said seat-operating links being approximately horizontal when the seat and back are in position for use and the connection of each of said seat-operating links with the seat and its 60 points of pivoting being approximately in line, whereby a movement of the seat and locking of the same in position is effected, 65 substantially as described.

3. In a reversible car-seat, the combination, 70 with the main frame, seat, and back, of a link at each end of the car-seat, connecting the upper part of the back with the main frame, forming the striker-arms, and a link at each end of the car-seat, pivoted to the main frame and the lower part of the back, each of said links being connected with the seat by a pin 75 engaging a slot, the said pin and the points of pivoting of the link being approximately in line and the said links being substantially 80 horizontal when the seat and back are in position for use, substantially as described.

In testimony whereof I affix my signature in presence of two witnesses.

JOHN LEMMAN.
